UNITED STATES PATENT OFFICE.

EARL J. R. BEATTEY, OF PROVIDENCE, RHODE ISLAND.

EYEGLASS-MOUNTING.

1,182,131.

Specification of Letters Patent.

Patented May 9, 1916.

Application filed July 31, 1912. Serial No. 712,431.

To all whom it may concern:

Be it known that I, EARL J. R. BEATTEY, a citizen of the United States, and resident of the city of Providence, in the county of Providence and State of Rhode Island, have invented certain new and useful Improvements in Eyeglass-Mountings, of which the following is a specification.

This invention relates to means for attaching bearing pads to eye-glass mountings, and has for its object to provide a cross-bar in the guard plate and a bearing pad having an integral tongue looped loosely around said bar whereby a universal 15 rocking motion of the pad is obtained.

A further object of the invention is the provision of a deep notch on the edge of the guard at the point where the bearing pad is attached and an opening a short distance 20 inward from the bottom of said notch thereby providing a bar between the two openings, by which construction the tongue on the bearing pad may be previously bent into the form of an open-mouthed hook and then 25 positioned on the guard while in such shape, rendering it only necessary to bend the tongue over slightly to cause its free end to pass through the second opening and firmly lock the pad in position on the guard.

With these and other objects in view, the invention consists of certain novel features of construction, as will be more fully described and particularly pointed out in the appended claim.

Of the accompanying drawings: Figure 1— is an enlarged plan view showing an eye-glass mounting with my improved guard and bearing pad mounted thereon. Fig. 2— is a greatly enlarged face view of the guard plate showing the concavo-convex end having the notch and bar to which latter the rocking pad is attached. Fig. 3— is a section on line 3—3 of Fig. 2 showing the concavo-convex shape of the end. Fig. 4— is 40 a plan view of the pad and the integral tongue blanked out of the sheet stock. Fig. 5— is a perspective view showing the tongue bent up into the form of a hook or loop. Fig. 6— is a central transverse section 45 through said pad showing the tortoise shell or celluloid facing on the pad. Fig. 7— is a central sectional view illustrating the tongue on the pad as having been bent into a hook form and set into the notch and in 50 position to be subsequently permanently attached by a slight bend of the tongue. Fig. 55

8— is a central sectional view illustrating the pad in operating position on the guard plate.

Referring to the drawings, 1 designates the lenses supported between the straps 2, which straps are joined together by the bridge member 3. On this bridge member is pivotally mounted the guard arms 4 to the outer end of each of which is attached the nose guard plate 5. This guard plate may be made in any suitable or desired shape from sheet metal, but is preferably made as illustrated in Fig. 2 to stand substantially in an upright position. The body portion 70 is comparatively narrow and has an enlarged roughened engaging surface 6 at its lower end, and an enlarged concavo-convex surface 7 substantially circular in outline at the upper or opposite end, but I do not wish 75 to be restricted to this exact construction as the upper end may be flat or substantially so instead of concavo-convex, and I may also attach a pad on each end of the nose guard, if desired, instead of on the upper 80 end only. The portion to which this pad is attached is provided with a deep notch 8 at its outer edge and also an opening 9 through it a short distance inward from the bottom of said notch thereby providing a 85 bar substantially vertically disposed.

The bearing pad 11, see Fig. 4, is constructed of an elongated body portion having a tongue 12 formed integral therewith, the edge of the pad being cut inward a short 90 distance to allow the tongue when bent to extend outward from the rear near the center of the plate. A roughened facing 13 of celluloid, tortoise shell, or other suitable material may be attached to the front surface of the pad, by rivets or other suitable means. In attaching this pad to the nose guard member the tongue 12 is first turned outward and then into a hook form with its free end slightly open or raised from the back of the pad as illustrated in Fig. 7, in which condition this tongue is passed into the notch 8 it being then only necessary to bend the tongue over to one side a short distance and its free end passes through the 100 opening 9 forming a loop around the bar 10, said free end resting against the rear face of the pad.

A feature of the invention is the construction whereby the tongue on the bearing 110 pad, which is formed integral therewith, may be first bent into a hook form before it

is positioned on the guard, thereby necessitating but a slight bend with a hammer or a small pair of pliers in order to attach it permanently in position on the guard. 5 Then again, by forming the tongue integral with the pad and bending the same in the form of a hook, it provides an extremely strong fastening which will never wear out or come apart. Then again, when it is desired to remove and replace this pad with another style or size, by my improved construction, it is not necessary to send it back to the factory, as any optician or mechanic can easily open the hook with a pair of pliers and remove the pad from the guard. 10 This change could not be accomplished if the pads were riveted in position on the guard. 15

I claim:

In an eye-glass mounting, a guard arm, 20 a nose guard mounted on said arm and provided with an opening through it near its center and a deep notch on its edge forming a bar between, a rocking pad having a single integral tongue bent into a substantially 25 hook form set into said notch and looped loosely around said bar whereby a universal rocking motion of the pad on the guard is obtained.

In testimony whereof I affix my signature 30 in presence of two witnesses.

EARL J. R. BEATTEY.

Witnesses:

HOWARD E. BARLOW,
E. I. OGDEN.
